(57) **CLAIM**

The ornamental design for a frame for a door as shown and described.

DESCRIPTION

FIG. 2.1 is a top view of a first embodiment of the frame for a door of the present invention.

FIG. 2.2 is an upper front left side perspective view of the frame for a door of FIG. 2.1.

FIG. 2.3 is an upper rear right side perspective view of the frame for a door of FIG. 2.1.

FIG. 3.1 is a top view of a second embodiment of the frame for a door of the present invention.

FIG. 3.2 is an upper front left side perspective view of the frame for a door of FIG. 3.1.

FIG. 3.3 is an upper rear right side perspective view of the frame for a door of FIG. 3.1.

FIG. 4.1 is a top view of a third embodiment of the frame for a door of the present invention.

FIG. 4.2 is an upper front left side perspective view of the frame for a door of FIG. 4.1.

FIG. 4.3 is an upper rear right side perspective view of the frame for a door of FIG. 4.1.

The broken lines depict a symbolic break in the article and form no part of the claimed design.
